(57) **CLAIM**

The ornamental design for a support for a solar panel, as shown and described.

DESCRIPTION

FIG. 1 is a perspective view of a support for a solar panel;
FIG. 2 is a front view of the support for a solar panel;
FIG. 3 is a rear view of the support for a solar panel;
FIG. 4 is a left side view of the support for a solar panel;
FIG. 5 is a right side view of the support for a solar panel;
FIG. 6 is a bottom view of the support for a solar panel; and,
FIG. 7 is a top view of the support for a solar panel.
The broken lines shown represent unclaimed subject matter
and form no part of the claimed design.
